UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed March 1, 1920. Serial No. 362,358.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines; and I do hereby declare the following to be a full, clear, and exact description of the invention, such as will enable others skilled in the art to which it appertains to make and use the same.

This invention relates to heel building machines, and it has special reference to such machines as are adapted to successively assemble, aline, press and nail the component lifts of a heel.

In applicant's Letters Patent of the United States No. 1,502,082, granted July 22, 1924, on an application, Serial No. 283, 20 693, filed March 20, 1919, there is disclosed a heel building machine of the general character above mentioned which comprises a heel assembling mechanism and a heel alining, pressing and nailing mechanism which 25 are so interconnected that they are operated as a single unit. In this prior machine the successively assembled heels are delivered upon a receiving device from which they are taken by the operator and manually transferred and placed into alining, pressing and nailing mechanism.

One of the objects of the present invention is to improve the construction and operation of the machine of the above mentioned 35 patent; and to provide a machine of this general type which shall be compact in arrangement, rugged and durable in construction, speedy and reliable in operation; and which shall be particularly adapted for full 40 automatic operation whereby the services of the operator may be dispensed with except in so far as the replenishment of the magazines with lifts is concerned.

To this end, one feature of the invention resides in the use of a heel assembling mechanism similar to that of the prior patent above referred to, which delivers the component lifts of a heel into one of a plurality of lift-receiving devices that are carried by a rotatable turret and rotated in steps through a plurality of operating stations, at which different operations upon the heels are concurrently performed. At 50 one of the stations, which may be considered

the first station, dry base-lifts are produced 55 from a magazine and positioned in the bottoms of the successive lift-receiving devices; at another and second station, lifts are produced from a series of magazines and after being coated with paste are delivered in 60 rapid succession in the form of loosely assembled heel-piles upon the dry base-lifts in the successive lift-receiving devices; at the third station, the heel-piles are presented for the inspection of the operator; and at 65 the fourth station the lifts forming the heel-piles are alined, pressed and nailed after which the heels are discharged upon a suitable conveyer which may be utilized to transfer them to another or other machines for 70 performing subsequent operations thereon.

Another object of the invention is to make provision for automatically arresting the 75 operation of the machine in the event that the assembling mechanism fails to deliver to the receiving devices one or more of the predetermined number of component lifts of the heels, whereby an opportunity is provided for the operator to supply the missing lifts and thereby obviate the possibility 80 of building heels of improper height.

With this object in view, one of the features of the invention resides in the use of an automatic measuring apparatus for determining the height of the loosely assembled lifts delivered to the receiving devices and for automatically disconnecting the machine from the source of power by throwing out its main clutch in the event that any of the lifts are missing. 85

A further object of the invention is to provide a simple, effective and reliable alining device for insuring an accurate alinement of the breast edges and the lateral edges of the component lifts of a heel. 90

The attainment of this end is accomplished through the agency of a feature of the invention which contemplates the co-operative action of a lift-receiving device embodying a breast gage and a lift alining device which is adapted for rectilinear movement towards the breast gage to effect the desired alinement. This alining device is provided with resiliently supported side-engaging alining members of a contour 100 corresponding to that of the ultimate side slope of the heel and these members function during the advancing movement of the 105

device to engage the lateral edges of the lifts and by a wiping movement to force them into proper position. In conjunction with these resiliently supported side-alining members, the alining device is provided with other rigid alining instrumentalities having the curvature and the pitch of the ultimate heel and which cooperate with the rounded rear edges of the lifts to positively force them into position and effect an accurate alinement of the breast edges thereof against the breast gage. After the heels have been thus alined and subsequently nailed, the alining device is withdrawn, during which movement it removes the heel from the lift-receiving device and deposits it upon the conveyer already mentioned.

Another object of the invention, having relation to the nail driving mechanism, is to provide automatic means for preventing the driving of a nail in the event that a heel is absent upon the lift-receiving device at the nailing station.

This object is attained by means of a feature of the invention which embodies the usual nail block for receiving and delivering nails into position to be driven. This nail block is spring actuated into delivering position and is normally restrained in its loading position. Heel detecting mechanism is employed for determining whether or not a heel is in position to be nailed and this mechanism operates by the engagement of a heel to release the normally restrained nail block only when a heel is present to be operated upon.

A still further object of the invention is to provide an improved and modified form of nail-feeding mechanism of the general type disclosed and claimed in Letters Patent No. 1,325,751, granted Dec. 23, 1919, to Joseph H. Pope and assigned to the United Shoe Machinery Corporation, which shall be simple and compact in arrangement and which shall operate with reliability to deliver nails successively and singly to the nail-driving mechanism.

Accordingly, another feature of the invention contemplates a nail-supply block of the Pope type having a series of rows of perforations for containing a supply of nails, which block is automatically actuated in steps in one direction to present the successive rows in position above and in alinement with the upper end of a single flexible nail tube of the usual form. The upper end of the single nail tube is actuated in a series of steps beneath the perforations in each row, whereby the nails contained therein are successively dropped into the tube and delivered into operative position to be driven. After all the nails in any row of perforations are delivered, the nail-supply block is advanced one step to properly position the next row of perforations for the

successive delivery of the nails contained therein.

These and other objects of the invention and features by means of which they are attained will become apparent to those skilled in the art from the following description of the preferred embodiment of the invention, as illustrated in the accompanying drawings, in which:

Figure 1 is a view in front elevation of a machine constructed in accordance with the present invention and illustrating particularly the cooperative relation of the heel assembling mechanism and the rotary turret; Fig. 2 is a view in front elevation and on an enlarged scale of the left hand end of the machine, the nail feeding mechanism being omitted; Fig. 3 is a view in end elevation of the machine, looking to the right in Fig. 2; Fig. 4 is a view, partially in section and partially in end elevation, taken on the section line 4-4 of Fig. 1; Fig. 5 is a sectional plan view on the line 5-5 of Fig. 3 of the left hand end of the machine, with certain parts removed for the sake of clearness; Fig. 6 is a view, partially in section and partially in plan, showing more clearly certain of the structural features of the apparatus shown in Fig. 5, the section being taken on the section line 6-6 of Fig. 3; Fig. 7 is a view in front elevation, and partially in section, on the line 7-7 of Fig. 5, illustrating the construction of the mechanisms located at the alining, pressing and nailing station; Figs. 8 and 9 are enlarged plan views of the alining device illustrated in different positions of operation; Figs. 10 and 10^a are respectively a view in enlarged perspective and a sectional view of certain members of the alining device; Figs. 11 and 12 are enlarged sectional views of the nail block and heel detector in different positions; Fig. 13 is a bottom plan view thereof; Fig. 14 is an enlarged view in front elevation of the nail feeding mechanism; Fig. 15 is an end elevation, looking from the right in Fig. 14, of a portion of the apparatus illustrated therein; Fig. 16 is an enlarged plan view of the nail feeding apparatus; Fig. 17 is a diagrammatic view of the gearing between the cam shaft of the assembling mechanism and the main drive shaft of the alining, pressing and nailing mechanism; and Fig. 18 is a detail view in rear elevation of a portion of the automatic trip mechanism.

Referring to the drawings illustrating the preferred form of the invention and with particular reference to Figs. 1 and 2 thereof, the heel building machine constituting the present invention comprises, in general, a lift assembling mechanism 20 and a turret type of alining, pressing and nailing mechanism 22. These mechanisms are conveniently disposed in side-by-side relation in

such manner that the heel-piles produced by the assembling mechanism 20 are automatically and successively delivered to the alining, pressing and nailing mechanism 22 which functions to perform various operations upon the loosely assembled heel-piles and to subsequently deliver the completed heels to a conveyer 24 which is adapted to transfer the heels to another machine or other machines for performing further operations upon the heels. The assembling mechanism 20 and the alining, pressing and nailing mechanism 22 are mechanically interconnected and driven from a common source of power through a main clutch 26 which may be thrown out manually or automatically to arrest the operation of the machine. The component mechanisms 20 and 22 are so combined and co-related as to constitute in effect a single unitary machine which is adapted for full automatic operation.

The assembling mechanism 20 is similar in construction and operation to the assembling mechanism disclosed in detail in applicant's Patent No. 1,502,082 hereinbefore referred to, and reference to this patent may be made for a full description of this mechanism. For this reason, and also inasmuch as the assembling mechanism pertains only indirectly to the present invention, except in so far as it performs a necessary function in the operation of the machine as a whole, only a brief, general description of this mechanism will be given. The main driving mechanism and the clutch, however, will be set forth in greater or less detail because of their direct bearing upon certain features of the alining, pressing and nailing mechanism 22 which necessitates a clear understanding of their construction, arrangement and location of parts and mode of operation.

In general, the lift assembling mechanism 20 comprises a plurality of lift magazines 28 for holding stacks of either wedge or even lifts. Suitable means is provided for concurrently producing a single lift from the bottom of each of the magazines and advancing the lifts so produced in a forward direction and depositing them in a row upon a continuously travelling belt or conveyer 30. The belt 30 serves to rapidly feed the lifts in series relation to a set of continuously driven feed wheels 32 which function to rapidly feed the lifts over a paste roll 34 by means of which the lower surfaces of all of the lifts are coated with paste. The feed wheels 32 perform a double function which includes the delivery of the pasted lifts into a suitable receiving device in the form of a loosely assembled heel-pile. In order to assist in securing a fairly accurate alinement of the lifts as they are delivered, a plurality of fingers 36 are adapted to be

positioned directly above the travelling belt 30 for temporarily alining the lifts as they are produced and deposited thereon.

Power is supplied to the assembling mechanism 20 and, in fact, to the machine as a whole, by means of a belt 38 from any suitable source through the agency of the usual fast and loose pulleys 40 and 42, both of which are loosely mounted upon the right hand end of a normally idle cam shaft 44 upon which are mounted a plurality of cams for governing the operation of certain of the actuating devices of the machine. For controlling the supply of power to the machine, a belt-shifter 46 of any ordinary form is employed and is secured to the end of a shift-rod 48 that extends horizontally across the front of the machine and is provided with a handle 50 in a position convenient to be grasped by the operator.

The fast pulley 40, while loosely mounted upon the cam shaft 44, is rigidly associated with a pinion 52 that meshes with a gear 54 which is secured to the end of a jack shaft 56, said shaft being suitably journaled in the frame of the machine. The jack shaft 56 is provided with a pinion 58 having a meshing engagement with a gear 60 that is fixed to an extended hub of a clutch disk 62 which is loosely mounted upon the cam shaft 44. The clutch disk 62 is provided with a series of lateral projections or teeth 64 with which a cooperating clutch lever 66 is adapted for engagement. The clutch lever 66 is bifurcated at its lower end to straddle a sleeve 68, and is pivotally mounted upon a pin 70 that projects through the bifurcated ends of the lever, through the sleeve 68, and through the cam shaft 44. The clutch lever 66 is urged by means of a spring 72 into operative position to engage one of the lateral projections of the clutch disk 62, but as shown in Fig. 1, is held in inoperative position out of engagement therewith by means of a wedge cam member 74. This member 74 is rigidly fixed to a transverse rotatable rod 76 that is suitably journaled in the frame. Towards the rear end of the rod an arm (not shown) is fixed, to which one end of a coiled spring 78 is attached, the other end being secured to a stationary pin 80 that is carried by the frame. The spring 78 therefore acts to normally maintain the wedge cam 74 in its operative position, as shown in Fig. 1, in which position the end of the clutch lever 66, during its rotating movement, is brought into engagement with the inclined cam surface thereof, which serves to force the cam lever out of engagement with the projections on the clutch disk 62.

A similar wedge cam 82 is provided upon a transverse rotatable rod 84 disposed parallel to the rod 76 and below the clutch disk 62, and concurrent operations of the two

wedge cams 74 and 82 are effected by means of a connecting equalizing link 86 that is pivotally associated with arms 85 and 87 that are respectively fixed to said rods.

5 The main clutch of the machine just described is normally maintained in inoperative position, as shown in Fig. 1, through the agency of the spring 78 but may be actuated to connect the cam shaft 44 to 10 the source of power by means of a dependent lever 88 that is fixed to the transverse rod 84 and which carries at its lower end a pin 90 that engages and supports a latch 92 that is provided on the right hand end of 15 a control rod 94. The other end of the control rod is secured to a member 96 that projects downwardly from a lever 98 (Figs. 2, 5 and 6) that is pivotally mounted at its inner end on a stationary pin 100 and 20 which is provided at its forward end with a handle 102.

This lever 98 and its associated handle 102 constitute the controlling lever for the machine, by means of which the operator 25 may manually throw the clutch in and out to start or interrupt the operation of the machine. The controlling lever 98 is adapted to occupy two positions, one as shown in Fig. 6 which is the stopping or inoperative 30 position and which effects the disengagement of the clutch as shown in Fig. 1, and the other, as shown in Fig. 5, which is the starting or operating position. It is clear that if the controlling lever 98 is moved 35 to the last mentioned position, the control rod 94 and latch 92 are moved to the right to cause the lever 88 to be swung in a counter-clockwise direction, whereby the wedge cam members 74 and 82 are retracted 40 to inoperative position to permit the clutch lever 66 to be forced inwardly into engagement with one of the projections of the clutch disk 62. This movement of the controlling lever must be manually effected and 45 is in opposition to the action of a spring 103 which is attached to the control lever 98 and also to the spring 78 which constantly tend to throw the control lever 98 and the wedge cams 74 and 82 into their 50 stopping positions.

In order to restrain the control lever 98 in its operative or starting position, as shown in Fig. 5, a latch 104 is secured to a longitudinally slidable plate 106 that is 55 carried on the upper side of the control lever. The latch 104 is normally engaged by a detent or stop 108 which functions to hold the lever and the main clutch in operative positions in opposition to the action of 60 the springs 78 and 103. A manual release of the latch 104, in the event that the operator desires to interrupt the operation of the machine, may be effected by squeezing an auxiliary handle 110 on the control lever 65 98 that is connected to the sliding plate

106 by a link 112 and which is pivotally mounted on a pin 114 carried by the control lever and normally maintained in its outer or operative position by means of a spring 116. When this auxiliary handle 70 110 is squeezed into position into engagement with the handle 102, the slide plate 106, and the latch 104 mounted thereon, are drawn forwardly to cause the latch to disengage the stop or detent 108, after which 75 the control lever 98 is moved to the left into its stopping position by the spring 103. Immediately upon such movement, the spring 78 serves to throw the wedge cams 80 74 and 82 into operative position to be engaged by the clutch lever 66, whereby said lever is thrown out of operative position and the clutch thereby disconnected.

Having described in greater or less detail the construction and operation of the lift assembling mechanism 20, together with its drive and manual control, reference may be had to Figs. 1 and 2 in connection with which the alining, pressing and nailing mechanism 22 will be set forth.

This mechanism embodies the main novel features of the present invention and is utilized in connection with the lift assembling mechanism 20, already described, to constitute a complete machine for the automatic building of heels. The mechanism 22 is disposed adjacent the assembling mechanism 20 for receiving the successive heel-piles produced thereby and after performing the necessary operations thereon for depositing the completed heels upon the conveyor 24 for transferral to other machines.

Referring particularly to Figs. 2 and 5, the mechanism 22 comprises, in general, a main supporting frame 120 carrying a drive shaft 122; a cam shaft 124; a rotatable turret embodying a central shaft 126 and a plurality of lift-receiving devices 128 that are adapted to be intermittently rotated in steps through a plurality of stations; means including an actuating ring 130 for depressing the lift-receiving devices prior to each rotational step of the turret; a base-lift magazine 131 containing a stack of dry base-lifts and a pusher 132 for successively feeding the lifts from the lower end of the stack and supplying them to the successive lift-receiving devices as they occupy the first or base-lift supply station; means including a cam 133 and a cooperating cam member or pawl 134 for effecting the automatic disengagement of the main clutch whenever there is a failure to deliver the proper number of lifts into the receiving-devices, a reciprocal alining device 136 embodying a slide 300, resiliently supported side-alining members 138 and rigid alining members 140 for cooperating with the loosely assembled heel-piles in the successive receiving-devices at 125 the last operating station for effecting the 130

lateral and breast alinement of the component lifts and for subsequently withdrawing and discharging the heels; means including a spring-pressed plunger 141 (Fig. 7) for subjecting the alined heel-piles to pressure; a reciprocating nail driver 142 for driving nails into the alined and pressed heel-piles in order to secure together the component lifts thereof; means including a wedge member 144 for rigidly backing the pressure applying plunger 141 and providing a positive support for the heel-pile during the nailing operation; means including a detector 146 and a spring actuated nail block 148 for positioning nails to be driven only when heels are present in the receiving devices to be operated upon; and an automatic nail feeding mechanism including a relatively movable nail supply block 150 (Fig. 16) and a flexible nail tube 152 for supplying nails one at a time to the nail block 148 in its loading position.

The supporting frame 120 comprises a pair of pedestals 156 and 158 (Figs. 2, 3, 4, 5, 6 and 7) which are attached to a bed-plate 159 and which support and are rigidly connected by an upper frame member 160, the upper end of which carries a bracket 162 upon which the nail feeding mechanism is mounted. The rotatable turret is supported upon a plurality of centers or pivots 166 and 168 (Figs. 2 and 7), the former being mounted in a bracket 170 secured to the bed-plate 159 of the frame, and the latter being carried by a depending bracket 172 that is secured to the frame of the lift assembling mechanism 20.

The drive shaft 122 of the mechanism 22 is journaled at one end in the side pedestal 174 (Fig. 1) of the assembling mechanism 20 and at the other end is rotatably mounted in a bearing 176 (Figs. 5 and 6) forming part of the pedestal 158. This shaft 122 is mechanically connected to be driven from the cam shaft 44 of the assembling mechanism 20 by means of cooperating gears 178, 180 and 182 (Figs. 5 and 17) and is provided at its opposite end with a mitre gear 184 which cooperates with a similar gear 186 for the purpose of driving the cam shaft 124. A plurality of cams 190, 192, 194, 196 and 198 (Figs. 6 and 7) are fixed to the cam shaft 124 and serve in conjunction with other elements to effect the proper timed-cooperation of the various operating mechanisms of the machine. Intermediate the ends of the drive shaft 122 a mitre gear 200 (Figs. 6 and 7) is fixed, which meshes with a corresponding gear 202 that is carried on a shaft 204 which is also provided with a gear 206. In cooperative engagement with this gear is another gear 208 that is mounted upon a stud 210 suitably carried by the bracket 170 of the frame and to which is also secured a driving pin arm 214 and a locking cam 216

which cooperate therewith to respectively drive and lock a quadrant plate 218 of a Geneva drive motion of the usual type. The quadrant plate 218 is fixed to the lower end of the main shaft 126 of the rotatable turret, and the relative proportions of the driving mechanism described, are so chosen that for each production of a heel-pile by the assembling mechanism 20, the turret is rotated through one step of a quarter of a revolution.

As already stated, the turret embodies a plurality of lift-receiving devices 128, and these devices are spaced 90 degrees from each other so as to be brought into the various operating stations at each quarter rotation of the turret by the Geneva motion just referred to. The lift-receiving devices 128 are of like construction and mode of mounting and, therefore, a description of only one of said devices will be given.

Referring particularly to Figs. 2, 5 and 7, each receiving device comprises a bottom plate 222 which is pivotally mounted upon a pin 224 and which is adjustable in position about said pin to accommodate the wedge or taper of the particular style of heels being built. The adjustment is effected by means of a set screw 226 which is carried by a supporting member 228 which also carries the pivot pin 224. Normally the bottom plate 222 is held down in engagement with said screw 226 by means of a spring 230. Cooperating with the bottom plate 222 is an upwardly extending plate 232 which constitutes a breast gage to engage the breast edges of the component lifts of the heel-pile. The breast gage 232 is also pivotally mounted upon the pin 224 and is adjustable in position by means of a set screw 234 to accommodate any desired slope of the heel breast. By properly adjusting the relative positions of the bottom plate 222 and breast gage 232, the receiving device may be adapted to receive heels of any desired characteristics.

The supporting member 228 upon which the receiving device is mounted is provided with a downwardly extending and vertically slotted portion 236 which is adjustably secured to one side of a vertically disposed carrier arm 238 by means of screws 240. By this adjustment, the receiving devices 128 may be set or adjusted to a height dependent upon the height of the heels to be built. The carrier arm 238 is cruciform in section and is mounted for parallel, vertical motion at the outer ends of a plurality of pairs of links 242 and 244, the inner ends of which are pivotally supported upon pins 246 and 248 respectively, said pins being carried by the central shaft 126 of the turret. In order to normally urge the receiving device to its uppermost position and to permit it to be depressed as the lifts are progressively delivered thereto, a spring 250

is connected at one end to a radially projecting arm 252 of a four-armed member that is fixed to the shaft 126 and at the other end to a screw eye 254 that is secured to the lower end of the carrier arm 238.

Prior to the rotational movements of the turret with its several lift-receiving devices 128, it is necessary to depress said devices in opposition to the several springs 250 and to maintain the devices in their depressed positions during the stepping movement in order that no obstructions shall be encountered and that the heel-piles shall be undisturbed in form during the transferral operation. For this purpose, each of the carrier arms 238 is provided with a radial projection 256 carrying a pivoted roll 258. The depression of the various lift-receiving devices 128 prior to each stepping movement of the turret is effected by means of the ring 130 which is provided with a hub 260 (Figs. 2 and 5) by which it is mounted for pivotal movement upon a supporting rod 262 extending horizontally across the front of the turret mechanism and mounted in the pedestals 156 and 174. This ring is of such diameter that on being swung downwardly about its pivotal support, it is brought into engagement with the rolls 258 of the several carrier arms 238, whereby said arms and associated lift-receiving devices 128 may be concurrently depressed in position. In this position the ring, and consequently the lift-receiving devices, is held during the rotational step while the ring serves as a circular track which is traversed by the respective rolls 258.

The actuation of the ring 130 is produced by means of a connecting rod 264 (Fig. 4), the upper end of which is pivotally connected to the side of the ring by a screw 266 and the lower end of which has a pivotal connection to one end of a bell crank lever 268 which is mounted for pivotal movement upon a stud 270. The lever 268 is provided with an upwardly extending arm carrying a roll 274 which cooperatively engages with a cam 276, the latter being carried by and fixed to the drive shaft 122. The roll 274 is maintained in cooperative engagement with the cam by the action of the various springs 250, and the cam is so designed as to periodically lower the ring 130 to effect the depression of the respective lift-receiving devices 128 prior to the stepping movement of the turret, after which the ring is raised in position to disengage the several rolls 258 and to permit the springs 250 to elevate the lift-receiving devices to their operative positions.

During the operation of the machine, the turret is intermittently rotated to advance the several lift-receiving devices 128 through a plurality of successive operating stations, namely,—a base-lift supplying

station, an assembling station, an inspection station and a station at which the heel-piles are alined, pressed, nailed and ejected. For purposes of explanation, the base-lift supplying station may be considered the initial station of the machine, adjacent to which the base-lift magazine 131 is located. This magazine comprises an upright member 278 (Figs. 3, 4 and 5) which constitutes part of a bracket 280 that is secured to the pedestal 158 and this bracket is provided with a horizontally extending member 282 which serves as a support upon which a stack of dry base-lifts rests. To confine the stack of lifts, a plurality of side plates 286 and 288 are adjustably secured to the upright member 278 by means of thumb nuts 290, in order to permit of the adjustment of the magazine to accommodate lifts of any size.

The lowermost lifts of the stack are successively removed therefrom and advanced into position upon the bottom member 222 of each lift-receiving device 128, as it occupies the first station, by means of the pusher member 132 which is periodically reciprocated and adapted to engage the edge of the lowermost lift, advance it over the supporting member 282, and deliver it to the receiving device. The lift being transferred is held under control during the transferring movement by means of a resilient guide finger 294 which engages the top surface of the lift. The pusher member 132 is adjustably secured to a member 296 by means of screws 298, in order to provide for the accurate positioning of the lifts in the lift-receiving devices, irrespective of the size of the lifts operated upon. The member 296 projects laterally from the slide 300, which constitutes a part of the alining device 136, and which is periodically reciprocated towards and from the axis 126 of the turret in ways 302 (Figs. 3, 4 and 7) that are secured to portions 304 projecting downwardly from the lower side of the horizontal member 306 constituting a part of the upper frame member 160. This slide 300 is box-like in construction, being provided with an upper wall 308, side walls 310, 312 and connecting ribs 314 and 316.

The reciprocations of the slide 300 are effected in the following manner. The outer ends of the side walls 310 and 312 carry a pin 318 (Figs. 3 and 7) which has a pivotal driving connection with a socket member 320 that is provided at the upper end of a tubular arm 322. This arm is mounted for telescopic sliding movement within a hollow lever 324 and is normally urged in an upward direction by means of a coiled spring 326 that is disposed within the openings in the arm 322 and lever 324. The lower end of the lever 324 has a pivotal connection 328 to the upper end of another

lever 330. A stop 332 constitutes a part of the lever 324 and is normally maintained in engagement with an inclined stop surface 334 of the lever 330 by means of a spring 336 which is seated in a socket 338 in the lever 330 and which acts against a projection 340 of the lever 324. The lever 330 forms a part of a yoke 339, the opposite ends of which are pivotally mounted upon a rod 342 that is suitably supported in the pedestals 156 and 158. The forward end of the yoke 339 is provided with an arm 344 carrying a roll 346 which cooperatively engages a cam path in the cam 198. This cam is designed to periodically reciprocate the slide 300 in proper timed relation to the other mechanisms of the machine to effect the delivery of a dry base-lift into each of the receiving devices 128 as they are successively positioned at the first station, and also to concurrently effect the alinement of the component lifts of the loosely assembled heel at the fourth station, as will hereinafter more fully appear. Obviously, the purpose of the spring-actuated telescopic connection is to insure proper operative engagement of the socket member 320 with the pin 318 as the cam 198 effects the actuation of the slide 300, while the yielding connection effected through the agency of the spring 336 between the arm 324 and lever 330 introduces an element of resilience in the driving mechanism for the slide to prevent undue strain or breakage in the event that an obstacle is encountered during its forward feed movement.

While the base-lift is being delivered to the lift-receiving device 128 occupying the first station, it is of course essential to maintain the lift-receiving device at the proper height for the transferral and deposition of the base-lift. For this purpose, a stop arm 350 (Figs. 3, 6 and 7) is provided for engaging the radially projecting lug 366 of the carrier arm 238 occupying the first station and for limiting the upward movement of the lift-receiving device in opposition to the action of its spring 250. This stop arm 350 constitutes a part of a bell crank that is pivotally mounted upon a stud 352 which projects from the side of the pedestal 158 and which is provided with another arm 358 dependent therefrom and carrying at its lower end an adjusting screw 360 which is adapted to engage the edge of a portion 362 of the pedestal 158. By suitably adjusting the set screw 360, the stop arm 350 may be properly positioned to limit the upward movement of the lift-receiving device in accordance with whatever height of heel is to be built. It is desirable, of course, to avoid any shock to the apparatus when the upward movement of the lift-receiving device is arrested by the arm 350. Therefore, a torsion spring 354 is disposed about the stud 352 in

such manner as to effect a gradual and yielding limitation to the elevating movement of the lift-receiving device.

Referring particularly to Fig. 2, the pasted lifts of the heel-pile are delivered in rapid succession upon the previously supplied dry base-lift in the lift-receiving device 128 at the second or assembling station, during which delivery the lift-receiving device is progressively depressed as the lifts are successively deposited. The apparatus is so constructed that during the delivery of the pasted lifts, the height of the heel-pile is measured to determine whether or not any of the lifts are missing, in which event means is provided for automatically releasing the detent or stop 108 which maintains the main control lever 98 in operating position, whereupon the main clutch of the machine is disengaged and the operation of the machine is discontinued. The accomplishment of this purpose is effected by the means and in the manner now to be described, which means may, for convenience, be termed—the automatic trip mechanism.

Having preliminarily adjusted the receiving devices 128 with respect to the carrier arms 238 in accordance with the height of the heels to be built, the measurement of the heel is determined by the depression of the carrier arm 238 upon which the lift-receiving device, being loaded, is mounted, and if the proper number of lifts have been delivered, an outwardly and radially projecting lug 366 (Fig. 2) is brought into engagement with one end of a lever 368 which is pivotally mounted at 370 intermediate its ends. However, if any of the lifts are missing, the lift-receiving device is not depressed far enough to cause the lug 366 to engage and actuate the lever 368.

In the event that the lever 368 is actuated, the end thereof, which engages an arm 372 (Figs. 2, 4, and 5) that is fixed to a transverse rod 374, is rotated in a counter-clockwise direction, thereby moving the pawl 134, which is also secured to the rod 374 at its rear end, into the position shown in Fig. 2 and against the action of a tension spring 376. The ends of the spring 376 are respectively secured to a pin 378 on an arm 380 secured to the rod 374 and to a bracket 382 which is secured to part of the supporting frame of the machine and supports the rod 374. In the position shown in Fig. 2, the pawl 134 which is pivoted directly beneath the drive shaft 122 is in such position as not to be engaged by the cam 133 secured to the shaft 122, so that the rod 374 remains in a position of rest.

However, if there is a failure to deliver one or more of the component lifts of the heel into the lift-receiving device, said device is depressed insufficiently to cause the lug 366 to engage the lever 368, so that the

pawl 134 is held by the spring 376 in a position in which it is engaged by the one or the other wings of the cam 133 during its operation. Such engagement serves to pull the rod 374 rearwardly, or to the right, as shown in Fig. 4, against a spring 385 which surrounds the rod, thereby causing a collar 386 which is secured to the rod to engage the upper end of a lever 388 that is pivotally mounted at 390 upon a lug depending from the bracket 382. Thereby, said lever is actuated in a clockwise direction against the action of a spring 392 to cause its lower end, carrying the spring-pressed detent or stop 108 to remove said detent from engagement with the latch 104 carried by the control lever 98. In this manner, the control lever 98 is automatically released and by means of the springs 103 and 78 is thrown into its 15 stopping or inoperative position, as shown in Fig. 6, under which circumstances the main clutch is disengaged and the operation of the machine automatically arrested. The operator is thus given an opportunity to supply the missing lifts after which he may 20 manually restore the operation of the machine by suitably actuating the control lever 98.

From the foregoing description, it will be understood that the automatic trip mechanism is so constructed and arranged that the clutch will be automatically disengaged at every cycle of the machine unless a proper number of lifts are delivered to the lift-receiving device at the assembling station, in which case the mechanism is actuated to prevent the functioning of the cam 133 and to permit the operation to continue.

Obviously, the inertia of the moving parts is such that the machine cannot be brought to rest instantaneously and, therefore, in order to prevent the breakage of the automatic trip mechanism, means is provided for positively retracting the pawl 134 from engagement with the cam 133 as soon as the control lever 98 has been released and actuated to its stopping position. This is effected through the agency of a control lever extension 394 (Figs. 4 and 18) which is normally engaged by the weighted end 40 of a lever 396 that is pivoted at 398 upon a member 400 secured to or constituting a part of the bracket 382. The upper enlarged end of the lever 396 rests against an arm 402 that conveniently constitutes an integral part of the pawl 134. With this construction, as soon as the control lever 98 is moved to its stopping position, its extension 394 turns the weighted lever 396 about its pivot 398 through the engagement of its upper enlarged end and the arm 402. The pawl 134 is thus positively retracted from engagement with the cam 133, whereby the parts of the trip mechanism are relieved of strain to which they would other-

wise be subjected by the inertia of the machine in coming to rest. Subsequently, the spring 385 forces the rod 374 and associated parts forwardly to their original positions. Manifestly when the control lever 98 is restored by the operator to its starting position, the weighted lever 396 resumes its normal gravity position, thus permitting the pawl 134 to be restored to its normal inoperative position and to function thereafter in the manner already described. 75

In order that the automatic trip mechanism may operate to properly throw out the clutch, irrespective of the height of the particular style of heels being built, it is necessary that the lift-receiving devices 128 be preliminarily adjusted with respect to the several carrier arms 238 by means of the sliding adjustable connections and adjusting screws 240 already referred to. 80

Concurrently with the supplying of a dry base-lift to the receiving device at the first station and the assembly of the pasted lifts in the receiving-device at the second station, the heel previously loosely assembled is presented at the third or inspection station for examination by the operator. Moreover, at the same time a previously assembled and inspected heel in another of the receiving devices occupies the fourth station at which 95 it is alined, pressed, nailed and ejected. As the lift-receiving device containing a heel is advanced from the inspecting station to the station last referred to, it, together with all of the other lift-receiving devices, is 100 maintained in its lowered position by the cooperative engagement of the ring 130 with the several rolls 258. When the rotational movement of the turret ceases, however, the ring 130 is raised to permit the springs 250 to elevate the lift-receiving devices to 105 their respective operative positions. At the alining, pressing and nailing station, the upward movement of the lift-receiving device therein is determined by the engagement of the uppermost lift with the wedge plate 406 (Figs. 7 and 11) that is detachably secured to a plate 408 that is bolted to the forward ends of side walls 410 and 412 (Fig. 4) of a 110 hollow box-like portion 413 of the upper frame member 160. 115

Having thus positioned the loosely assembled heel at the fourth operating station, the lateral and breast edges of the component lifts thereof are alined by means of the reciprocable alining device 136 (Figs. 8, 10 and 11) which embodies the resiliently supported side-alining members 138 and the rigid alining members 140. 120

The alining device 136 comprises the slide 300, already described in connection with the base-lift pusher member 132, to the side walls 310 and 312 of which are secured resilient members 416 which project forwardly 125 and to which are detachably mounted the 130

side-alining members 138. The inner surfaces of these members are so shaped and inclined as to correspond to the ultimate side slope of the heel to be produced, and each member 138 is provided with a shoulder 418, the purpose of which will be later set forth. The rigid alining members 140 are detachably secured by means of screws 422 to the forward ends 424 of the side walls 310 and 312 of the slide 300, and the forward extremities of these alining members 140 are so curved and inclined as to conform to the curvature and the ultimate rear slope or pitch of the heel to be built. When building heels of different styles, the alining members 138 and 140 are replaced by similar members of the proper dimensions and configuration.

The alining device 136 is reciprocated as a unit in a rectilinear path towards and from the lift-receiving device 128 occupying the fourth station by means of the cam 198 and the actuating mechanism operated thereby and hereinbefore described in connection with the pusher member 132. Prior to the advancing movement, the alining device 136 occupies the position shown in Fig. 8. Upon advancing the alining device, the forward ends of the resilient supporting members 416 and also the side alining members 138 successively engage the lateral surfaces of the heel held in alining position in the receiving device. As the alining device is advanced, the resilient supporting members 416 and side-alining members 138 are forced outwardly, and by reason of their wiping engagement with the lateral edges of the lifts, effect the lateral alinement thereof, while they always tend to force the heel against the breast gage 232. Before the alining device reaches its forward limit of travel, the shoulders 418 of the side-alining members 138 are advanced beyond the heel and are snapped into the position shown in Fig. 9. At the same time, the rigid alining members 140 are brought into engagement with the curved rear edges of the lifts and positively force them forwardly against the breast gage 232 of the lift-receiving device, thereby insuring the proper alinement of the breast surface of the heel. Substantially concurrently with these operations, the forward ends of the resilient supporting members 416 are brought into engagement with inclined cam surfaces 426, constituting a part of the bracket 172 that is suitably mounted upon the frame. The cooperative engagement of these cam surfaces 426 with the forward extremities of the resilient supports 416 causes the side-alining members 138 to be squeezed together under considerable pressure, during which action the final lateral alinement of the lifts is effected and insured.

After the heel is thus accurately alined in the receiving device 128 at the fourth sta-

tion, it is held in this condition while the heel is subjected to vertical pressure by means of the pressure applying plunger 141 which engages the lower end of the carrier arm 238.

To carry out this function of the apparatus, the plunger 141 is mounted for vertical sliding movement in bearings 430 (Fig. 7) and 432 constituting part of the frame, and said plunger is surrounded by a heavy pressure-applying spring 434 which is positioned between the bearing 430 and a collar 436 (Figs. 6 and 7) that is secured to the plunger and which is provided with oppositely extending lateral pins 438. These pins are received in slotted bifurcated ends of an actuating lever 440 that is pivotally mounted upon the rod 432 and which carries a roll 442 that traverses the periphery of the cam 194. The spring 434 serves to maintain the roll in engagement with the cam and the cam is designed to permit the spring to raise the plunger 141 into engagement with the lower end of the carrier arm 238 occupying the fourth station at a time after the heel has been raised into engagement with the wedge plate 406 and alined in the manner described. The spring 434 therefore operates to cause the plunger 141 to act against the carrier arm 238 and subject the heel to a heavy squeezing pressure.

Immediately upon the application of pressure to the heel, the cam 190 operates to permit a spring 444 (Figs. 6 and 7) to actuate a bell crank lever pivotally mounted on the rod 342 and comprising an arm 445 carrying a roll 446 and another downwardly projecting arm 448 connected to the wedge member 144, whereby said wedge member is projected beneath the lower end of the plunger 141. Thus a rigid backing for the plunger and the receiving device is provided during the subsequent nailing operation.

The next operation to be performed at the fourth station is the nailing together of the component lifts of the heel, while the heel is held in alinement and under pressure in the manner already described. To the accomplishment of this end, the nail driver 142 (Figs. 2, 7 and 11) is provided at the lower end of a nailing plunger 450 that is adapted for vertical reciprocation within an apertured portion 452 of the upper frame member 160. Intermediate its ends, the plunger 450 is provided with a pair of spaced collars 454 between which are positioned a pair of rolls 456 that are carried by the bifurcated end of a lever 458 which is mounted for pivotal movement upon a stud 460 that is carried in suitable lugs forming a part of the frame member 160. The lever 458 carries intermediate its ends, a stud 464 that projects outwardly at

both sides thereof and to the respective ends of which are pivotally connected a pair of downwardly projecting connecting rods 466 (Fig. 3). The lower ends of these rods are secured to a cross bar 468. The upper end of a rod 470 (Fig. 7) is attached to the mid-point of the cross bar 468 and the lower end thereof has a pivotal connection with one end of a lever 472 that carries a roll 474, the latter being maintained in cooperative engagement with the cam 192 by means of a coiled spring 476. The spring 476 therefore serves to maintain the nail driver 142 in raised position while the driving movement thereof is effected positively by the operation of the cam 192 which actuates the nail driver periodically to drive nails into the heels at the proper time with respect to the operation of the other mechanisms of the machine.

Nails are successively fed into position to be driven by the continuously reciprocating nail driver 142 through the agency of the nail block 148 which is adapted to be reciprocated from its loading position, shown in Fig. 11, in which it receives a nail from the nail tube 152, to a nail-driving position, shown in Fig. 12, in which it positions the nail previously received for the driving operation. The nail block 148 comprises a slide-plate 478 (Figs. 4, 7, 11, 12 and 13) that is mounted for sliding movements in ways 480 that are secured to the upper wall 482 of a box-like portion 413 of the frame member 160. Secured to the forward end of the slide-plate 478 is a recessed nail-receiving member 484 which is adapted to contain and transfer the nails from the nail tube 152 to operative position. The lower end of this member 484 is adapted to slide upon the upper surface of the plate 408.

The movement of the nail block 148 from its loading position to its operative position is effected by means of a coiled spring 488 which surrounds a rod 490 that projects rearwardly from a downwardly projecting portion 492 of the slide-plate 478. Under normal conditions the nail block 148 is restrained in its inoperative loading position by means of a latch 494 having a shouldered extremity 496 that engages the upper edge of a lateral extension 498 of the portion 492. The latch 494 is pivotally mounted upon a screw 500 threaded into the side wall 412 of the box-like portion 413 of the frame member 160. Connecting the lever 494 with another lever 504 is a link 506, and the lever 504 is pivotally mounted upon a rod 508 that extends laterally and is mounted in the side walls 410 and 412 of the box-like frame portion.

The outer end of the lever 504 carries the heel detector 146 which projects through a

suitable opening in the plate 408 and into position beneath the wedge plate 406 such that it may be engaged and actuated by a heel that is raised into engagement with the wedge plate 406 in the manner already described. Under these conditions the detector 146 is pushed upwardly causing a corresponding upward movement of the lever 504 and also of the connected latch 494, with the result that the shouldered end of the latch 494 is raised out of engagement with the lateral extension 498 of the slide plate 478. Thus, the nail block 148 is released and its actuating spring 488 functions to project the nail block forwardly into the position shown in Fig. 12, in which position the aperture of the nail-receiving member 484 registers with the nail driver 142 and also with a nail hole 510, thereby delivering a nail into position to be driven by the next operative movement of the nail driver. The forward movement of the nail block 148 is determined by an adjustable stop in the form of a set screw 512 which is carried by a plate 514 secured to the cylindrical portion 452 of the frame member 160, the end of said set screw being positioned to be engaged by the forward edge of the sliding plate 478.

By reason of the construction just described, it will be understood that the nail block 148 is released to present a nail into driving position only when a heel is present in the lift-receiving device 128, as it is raised into operative position. Of course, if a heel is absent, the detector 146 is not engaged and actuated and therefore the latch 494 remains in its restraining position to prevent the forward movement of the nail block. Therefore, no nail is positioned to be driven and the subsequent driving movement of the nail driver 142 is rendered inoperative and idle.

Even when a heel is absent from the receiving device 128, the detector 146 would be engaged and actuated by the bottom member 222 of said device unless means were provided for preventing the occurrence of such a condition. This means comprises a limit stop 516 (Fig. 7) which forms an upwardly projecting part of the upper plunger bearing 432 and which is located to be engaged by the radially projecting lug 366 of the carrier arm 238 in the event that the upward movement thereof is not limited by the presence of a heel in the receiving device.

Nails are successively supplied to the nail block 148 in its loading position through the flexible nail tube 152 from a nail-feeding mechanism carried by a frame bracket 162 that is bolted to the upper frame member 160, and upon which is mounted the nail-supply block 150. This nail-supply block 150 is provided with a plurality of rows of perforations 524 (Figs. 14, 15 and 16) each

of which is adapted to contain a nail. The block is detachably mounted upon a movable carriage 526 that is adapted for sliding longitudinal movement in ways 528 which extend the full length of the frame bracket 162. The carriage 526 is provided at its forward side with a plurality of lugs 530 which serve as bearings for a rotatable rod 532, the ends of which are provided with 10 arms or keepers 534 which are spaced apart the proper distance to engage the opposite ends of the block 150 and hold it positively in position upon the carriage. The keepers 534 may be readily raised to release the block for replacement purposes by means of upturned extensions 536 constituting parts of the keepers 534.

When the nail-supply block 150, filled with nails, is positioned on the carriage 526, as shown in Fig. 16, all of the nails in its perforations, with the exception of those in the first or right-hand row, rest upon the solid upper surface of the horizontal member 540 of the frame bracket 162, while the 20 nails in the first row of perforations rest upon the upper surface of a transversely disposed feed-bar 542. The feed bar 542 is mounted in bearings 544 and 546 in the bracket frame 162, and the upper surface 25 thereof lies in the same plane as the upper surface of the horizontal member 540 of the bracket frame. This feed-bar 542 contains a vertical nail opening 548 (Fig. 14) which 30 communicates with the upper end of the flexible nail tube 152 which is secured to the bar in registry therewith.

In order to deliver nails successively from the nail-supply block 150 for transferral through the nail tube 152 to the loading 40 station of the nail block 148, means is provided for intermittently stepping or feeding the feed-bar 542 so as to bring the nail hole 548 successively into registry with the successive perforations 524 of the first row, it being understood that the nails contained 45 in these perforations will thereby be successively dropped through the feed tube to the nail-receiving member 484 of the nail block in the loading station.

Having in mind that the nail block 148 is released to feed a nail only when heels are present in the receiving devices, it is clear that the delivery of nails from the nail supply block 150 to the nail block 148 should only be effected in the event that the nail block has just been released to supply a nail to the nail driver 142. To attain this result, the mechanism for resetting the nail block is utilized for effecting the stepping feed movements of the feed-bar 542. The nail block 148 is reset to its loading position by means of an arm 550 (Fig. 12) which is secured to the rod 508 and which 50 is adapted for continuous oscillatory movements through the agency of an arm 552,

also secured to the shaft 508, and which is pivotally connected to a rod 554 having a pivotal connection to a lever 556 (Figs. 6 and 7) mounted upon the shaft 342 and carrying a roll 558 that engages the cam 196. The roll is held in operative engagement with the cam 196 by a spring 560, and the cam is arranged to permit the periodic oscillation of the nail block setting arm 550. If the nail block has been 70 released and occupies its operating station, as shown in Fig. 12, the oscillating resetting arm 550 engages the lower end of the lug 492 of the sliding plate 478 and forces said plate back into its loading position, thereby permitting the latch 494 to drop into operative restraining position, as shown in Fig. 11.

The advancement of the feed-bar 542 and the consequent delivery of nails to the nail block only just subsequent to each resetting operation thereof is insured by utilizing the resetting movement of the nail block for actuating the feed-bar 542. A lever 564 is, therefore, mounted on a rod 566 (Figs. 2 and 11) which is suitably carried in the frame member 160. This lever 564 is so positioned that its lower end is adapted to be engaged by the right-hand end of the sliding plate 478 of the nail block 148 so 95 that said lever is actuated toward the right in Fig. 11 whenever the nail block is reset. This movement is transmitted for the intended purpose by means of an arm 570 that is secured to the rod 566 and which 100 has a universal connection 572 to the lower end of a connecting rod 574, the upper end of which is pivotally connected to one arm of a bell crank 576 (Figs. 14, 15 and 16), said bell crank being pivotally mounted 105 upon a stud 578 that is threaded into a boss of the frame bracket 162. The other arm of the bell crank projects upwardly and is provided with a portion 582 for engagement with a roll 584 that is carried at the outer end of a lever 586 pivotally mounted upon a stud 588 projecting downwardly from the horizontal member 540 of the bracket frame 162. The other end of the lever 586 is bifurcated and supports between its arms 110 and upon a pivot 590 a feed pawl 592 which is normally held in engagement with one of a plurality of teeth 594 provided on the side of the transversely movable feed-bar 542 by means of a spring 596 that operates 115 upon an extension 598 of said pawl. The roll 584 is normally maintained in engagement with the portion 582 of the bell crank 576 by means of a spring 600 which is connected between the lever 586 and a point 120 on the bracket frame 162. This spring further serves the purpose of maintaining the arm 564 in position to be engaged by the nail block 148 during its resetting operation, as shown in Fig. 11.

During each resetting operation of the nail block, the arm 564 is rotated to cause the bell crank 576 to operate upon the roll 584 in such manner as to actuate the feed pawl 592 toward the rear. By this movement the feed pawl effects an actuation of the transverse feed-bar 542 through a single step, corresponding to the width of one of the teeth 594, which in turn corresponds to the spacing of the perforations 524 of the nail-supply block 150. Therefore, the nail opening 548 of the feed-bar 542 is positioned in registry beneath the first perforation to permit the nail contained therein to be dropped into and through the nail tube 152 and thence into the recess of the nail block occupying its reset loading position.

As soon as the feed-bar 542 has been actuated a single step, it is retained in that position by means of a locking pawl 604 that cooperates with the teeth 594 of the bar and which is pivotally mounted upon a stud 606 projecting downwardly from the bracket frame 162. Integrally associated with the pawl 604 is an arm 608 that projects to the right and terminates in a more or less pointed end 610. This pointed end is adapted to cooperate with one or the other of a plurality of notches 612 and 614 that are provided in one end of a lever 616, the latter being pivotally mounted upon a stationary stud 618 suitably supported in the frame bracket 162. The lever 616 projects beyond the pivot pin 618 and is attached to one end of a tension spring 620, the other end being suitably fixed to the frame. The spring 620, therefore, serves through the mechanism just described to yieldingly maintain the locking pawl 604 in operative position so long as the pointed end 610 of the arm 608 is positioned in the notch 612.

In the manner set forth, the transverse feed-bar 542 will be successively actuated in steps to effect the successive delivery of the nails in the perforations of the first row. During these feeding movements, means is provided for storing up energy for resetting the feed-bar 542 after the nail hole 548 has traversed all of the perforations of the first row. This means embodies a long lever 624 (Fig. 16) that is pivotally mounted at 626 on the bracket frame and which is provided near its free end with a longitudinal slot 628 through which projects a pin 630 that is fixed to the feed-bar 542. The lever 624 also embodies a lateral extending arm 632 to which one end of a heavy spring 634 is attached, the other end thereof being secured to the frame bracket 162 by an eye 636. With this construction it is evident that as the feed-bar 542 is actuated through its successive feed steps, as already described, the lever 624, by reason of its pin-and-slot connection with said bar 542, will be swung

about its pivot 626. In so doing, it will extend and store energy in the spring 634, which energy is capable of use for resetting the feed-bar 542, provided suitable means are employed to release the feed pawl 592 and the locking pawl 604 from engagement therewith.

For this purpose the lever 624 is provided with an upwardly extending pin 640 that is adapted to engage an end piece 642 of a U-shaped arm 644 that is integral with or fixed to the latch 604 and the arm 608. Upon the engagement of the pin 640 with the end of the arm 644, the locking pawl 604 is rotated out of engagement with the teeth 594, during which movement the pointed end 610 of the arm 608 is forced into the notch 614 of the lever 616. The movement of the arm 608 is transmitted through a link 646 to one end of a lever 648 that is pivotally mounted upon a fixed stud 650 projecting downwardly from the frame bracket 162. The other end of the lever 648 carries a pin 652 that projects beneath the feed pawl 592 and which, when motion is imparted thereto in the manner described, serves to withdraw said pawl from operative engagement with the teeth 594 and to maintain it in its withdrawn inoperative position. Under these conditions the spring 620, which formerly served to yieldingly hold the locking pawl 604 in locking position, now serves to yieldingly hold said pawl, together with the feed pawl 592, in their withdrawn and inoperative positions.

As soon as the two pawls 592 and 604 are withdrawn from engagement with the teeth of the feed-bar 542, it is clear that the spring 634 is permitted to utilize its stored energy in swinging the lever 624 and consequently the bar 542 back to their initial positions. Under these circumstances, the feed-bar 542, with its nail hole 548, is in readiness for another series of feed movements to successively deliver the nails in the second row of perforations, provided means is employed for stepping the nail-supply block 150 to the right to bring the second row of perforations in alignment with the path of travel of the nail hole 548 in the feed-bar.

The feed movements of the nail-supply block 150 are effected by means of a clock spring 654 (Figs. 14, 15 and 16), which is wound around and secured to a pin 656 that projects through and is secured to a casing 658, the latter being bolted to the frame bracket 162. The free end of the spring 654 is attached, by means of a screw 660, to the left-hand end of the carriage 526, and said spring lies in a slot 662 in the upper surface thereof and constantly tends to move the carriage to the right. This tendency of the actuating spring 654 to move the carriage and the nail-supply block 150, is restrained

by the one or the other of a plurality of locking pawls 666 and 668 which are respectively adapted to cooperatively engage with teeth 670 in the forward edge of the carriage

5 526. The pawl 666 is pivotally mounted upon a pin 672 and has a pin-and-slot connection 674 with one end of a long link 676 that extends rearwardly and is connected to one end of a link 678 by a pivot pin 680 that 10 is sufficiently long to project upwardly from the link 676 into position to be engaged by the inclined surface 682 of the lever 624, when said lever and associated feed-bar 542 are actuated to their extreme position. The 15 other end of the link 678 is mounted upon the fixed pivot pin 618 which carries the lever 616. Toward the forward end of the long link 676, an upwardly projecting pin 684 is provided which is adapted to be engaged by the inclined surface 686 at the free end of the lever 624 when said lever occupies the position shown in Fig. 16.

The actuation of the pawl 668 is effected by movements of the long link 676 in a manner to be set forth, and for this purpose the forward end of the link 676 is pivotally connected to an arm 688 pinned to the lower end of a rod 690 that is suitably carried by the frame bracket. The upper end of the 20 rod is provided with a fixed arm 692 that is yieldingly maintained in engagement with a pin 694 carried by the pawl 668 by means of a grasshopper spring 696.

By virtue of the construction set forth, 25 the nail-supply block 150 is allowed to step forward a single row after the nails in the perforations of each row have been delivered through the feed tube to the nail block, and this is accomplished in the following manner,—assuming the component parts of the nail feed mechanism to occupy 30 the positions shown in Fig. 16. As the transverse feed-bar 542 is advanced step-by-step into its extreme position, at which time 35 the locking pawl 604 and feed pawl 592 are withdrawn and released in a manner already described, the inclined surface 682 of the free end of the lever 624 is brought into engagement with the connecting pin 680 at the rear end of the long link 676. The link 676, therefore, is actuated a slight amount in a rearward direction, which causes the pawl 668 to be dropped into the adjacent tooth of the carriage rack 670. 40 At the same time, the pawl 666 is retracted from engagement with its tooth. At the time when the pawl 668 is positioned and the pawl 666 retracted, only a slight clearance or space will exist between the end of 45 the pawl 668 and the shoulder of the next adjacent tooth 670 to be engaged, as will be noted from an inspection of Fig. 16. Therefore, the clock spring 664 is capable 50 of moving the sliding carriage 626 only a very slight amount at this time. This

amount, however, is sufficient to insure that the pawl 666, when next actuated into latching position, shall be so positioned as to engage the next succeeding tooth.

After having actuated the pawls 666 and 668 in the manner set forth, the feed-bar 542 and lever 624 are reset to their initial positions by the spring 634. During the end of this movement, the inclined surface 686 of the free end of the lever 624 is 70 brought into engagement with the pin 684, thereby actuating the long link 676 in a forward direction to positively release the pawl 668, which has previously been swung into locking position, and concurrently to 75 throw the pawl 666 into latching position. Upon this operation, the clock spring 664 functions to advance the carriage and nail-supply block the remainder of a full step to bring a second row of perforations over the 80 path of travel of the nail hole 548 in the feed-bar 542.

Concurrently with the operation just described, a pin 700 projecting laterally from the side of the feed-bar 542 is brought into 90 engagement with the rear surface of the end piece 642 of the U-shaped arm 644, whereby said arm is actuated to rotate the locking pawl 604 into operative position. During 95 this action, the pointed end 610 of the arm 608 is snapped into the notch 612, thereby causing the spring 620 to yieldingly maintain the latch 604 in working position. The movement of the arm 608 is transmitted 100 through the link 646 to the lever 648 in such manner that the pin 652, which has been acting to hold the feed pawl 592 in 105 inoperative position, is returned to its normal position to permit said feed pawl to resume its operative relation with the teeth 110 594 of the feed-bar 542. Having thus restored the feeding mechanisms to their 115 initial positions, the successive feeding movements of the feed-bar 542 and the intermittent advancing movements of the nail-supply block 150 are repeatedly continued 120 in the manner already described, until all of the nails in the nail-supply block have been delivered through the nail tube to the 125 nail block and nail driving mechanism.

The nail feeding mechanism is then prepared for further operation by manually resetting the carriage 526 and nail-supply block 150 to their initial positions, during 130 which operation energy is stored in the clock spring 664 for subsequent use. Having thus reset the nail-supply block 150, the keepers 534 are released and the empty block removed and replaced by another block that is filled with nails. The nail feed mechanism is then in readiness to continue its operation in the manner described.

Having described the construction and operation of the alining, pressing, nailing, and nail feeding mechanisms, all of which 130

perform their functions at the fourth station of the machine, consideration will be given to the means for and manner of effecting the discharge of the heels from the lift-receiving devices 128 and their deposition upon the conveyer 24 for transferral to other machines for performing subsequent operations upon them.

Subsequent to the nail-driving operation at the fourth station, the cam 190 (Fig. 7) through mechanism actuated thereby, withdraws the wedge member 144 from beneath the spring-pressed pressure-applying plunger 141, after which the cam 194 serves through its associated mechanism to depress the plunger 141 against the action of the spring 434, thereby relieving the heel from heavy pressure and leaving it in the receiving device 128 and sustained in position merely through the action of the spring 250. Thereupon the cam 198 functions to effect the withdrawal of the alining device 136 (Fig. 9) and the base-lift pusher member 132 that is secured to the slide 300 thereof. As the alining device 136 is withdrawn, the ends of the resilient supporting members 416 are disengaged from the cam surfaces 426 and the shoulders 418 of the side-alining members 138 are brought into engagement with the breast of the heel. During the continued withdrawing movement, the heel is removed from the lift-receiving device 128 and is carried back to a position above the conveyer 24.

At this time a plurality of downwardly projecting members 704 (Figs. 3 and 5) that are secured to the forward ends of the respective resilient supporting members 416 are brought into engagement with inclined cam members 706 which project upwardly from the cross-piece 468 of the nail-driving mechanism. These cam members 706 therefore cooperate with the members 704 to spread apart the resilient supporting members 416 carrying the side-alining members 138, whereby said alining members are disengaged from the heel which, being no longer supported thereby, is permitted to drop and be deposited upon the conveyer 24.

The rotary turret with its several lift-receiving devices, together with the various operating mechanisms at the respective operating stations of the machine, are then in readiness to repeat the cycles of operation hereinbefore described. The machine therefore continues to function in the manner set forth to assemble, aline, press, and nail heels with reliability and rapidity, and to deliver the completed heels successively to the conveyer 24 which transports them to other machines or mechanisms for performing subsequent operations thereon.

Those skilled in the art will readily understand that the machine of the present invention is fully automatic in its operations

and, by reason of the multiple operating stations and its peculiar mode of operation, is adapted to build accurately alined heels of a predetermined height with unusual expedition.

Although the invention has been illustrated and described as embodying specific structural details, arrangements and locations of parts, and mode of operation, it should be understood that many modifications and variations therein may be made while still retaining the benefits of the invention and without departing from the spirit thereof. Therefore, only such limitations should be imposed as are indicated in the appended claims.

That which is claimed as new is:—

1. A heel-building machine having, in combination, means for periodically delivering successive series of heel lifts in a row, and means for assembling each row of lifts in the form of a heel-pile including a rotatable turret comprising a plurality of lift-receiving devices and rotatable in steps to bring said receiving devices successively into position to receive a series of lifts in a pile as the lifts comprising said series are advanced in succession thereto.

2. A heel-building machine having, in combination, means for periodically delivering successive series of heel lifts in a row, and means for assembling each row of lifts in the form of a heel-pile including a rotatable turret comprising a plurality of lift-receiving devices adapted to be moved through successive stations in one of which said devices receive a series of lifts in a pile as the lifts comprising said series are advanced in succession thereto, and means for operating on the heel-piles thus produced after their removal from the assembling station by rotation of the turret.

3. A heel-building machine having, in combination, means for periodically assembling a plurality of heel lifts in the form of a heel-pile, a rotatable turret comprising a plurality of lift-receiving devices adapted to be moved through successive stations, in one of which said devices successively receive the assembled heel-piles, and means disposed at another station for alining and securing together said heel-piles.

4. A heel-building machine having, in combination, a rotatable turret comprising a plurality of lift-receiving devices, means for intermittently rotating said devices through a plurality of stations, means for pasting a plurality of lifts and assembling them into said receiving devices at one of said stations, and means at another station for alining the component lifts, subjecting them to pressure and nailing them together.

5. A heel-building machine having, in combination, a rotatable turret comprising

5 a plurality of lift-receiving devices, means for intermittently rotating said devices through a plurality of stations, means for assembling a plurality of lifts into said receiving devices at one of said stations, and means operating upon said assembled lifts while in said receiving devices and after they are removed from said receiving station for alining said lifts, securing them together and effecting their discharge.

10 6. A heel-building machine having, in combination, means for assembling a plurality of lifts in the form of a heel-pile, a rotatable turret comprising a plurality of lift-receiving devices into which the heel-piles are successively assembled for transferring said heel-piles to other stations, and means to which the heel-piles are transferred by said turret for alining said heel-piles, subjecting them to pressure, nailing together the component lifts thereof and effecting the discharge of said heel-piles.

15 7. A heel-building machine having, in combination, means for assembling a plurality of lifts in the form of a heel-pile, a rotatable turret comprising a plurality of lift-receiving devices into which the heel-piles are successively assembled for transferring said heel-piles to other stations, means disposed at another station and reciprocable towards and from the axis of said turret for laterally alining the lifts of a heel-pile during its inward movement and for removing the heel-pile during its outward movement, and means operable between the inward and outward movements of said reciprocable means for nailing together the component lifts of the heel-pile.

20 8. A heel-building machine having, in combination, a rotatable turret comprising a plurality of lift-receiving devices movable in steps through a plurality of stations, means at one station for assembling a plurality of pasted lifts in the successive receiving devices in the form of heel-piles, means at another station for alining, nailing and discharging said heel-piles, and means at another station for positioning dry base-lifts in the successive receiving devices.

25 9. A heel-building machine having, in combination, an intermittently rotatable turret comprising a plurality of lift-receiving devices adapted to be moved through successive stations, means for assembling a plurality of lifts in the form of heel-piles in the successive receiving devices at one station, and means operable concurrently with the assembling operation for alining and nailing a previously assembled heel-pile in another receiving device at another station.

30 10. A heel-building machine having, in combination, an intermittently movable lift-receiving device adapted to be advanced

35 through a plurality of stations, means at one station operable during periods of rest of said lift-receiving device for simultaneously producing, and then pasting and delivering a plurality of lifts into said receiving device in the form of a heel-pile, and means at another station for operating upon said heel-pile.

40 11. A heel-building machine having, in combination, an intermittently movable lift-receiving device adapted to be advanced through a plurality of stations, means at one station operable during periods of rest of said lift-receiving device for producing, pasting and delivering a plurality of lifts into said receiving device in the form of a loosely assembled heel-pile, and means at another station for alining the component lifts of the heel-pile and securing them together.

45 12. A heel-building machine having, in combination, means at one station for assembling a plurality of lifts in the form of a heel-pile, a rotatable turret, a plurality of lift-receiving devices carried thereby into which the lifts are assembled successively, said devices being independently and yieldingly maintained in raised position and adapted to be depressed as the lifts are progressively deposited therein, means for rotating the turret in steps to move the lift-receiving devices through successive stations, means at one of said stations for operating upon the lifts, and means for depressing all of said lift-receiving devices prior to each rotational step of the turret and for permitting said devices to be yieldingly raised after the turret has come to rest.

50 13. A heel-building machine having, in combination, means at one station for assembling a plurality of lifts in the form of a heel-pile, a rotatable turret, a plurality of lift-receiving devices carried thereby into which the lifts are assembled successively, said devices being independently and yieldingly maintained in raised position and adapted to be depressed as the lifts are progressively deposited therein, means for rotating the turret in steps to move the lift-receiving devices through successive stations, means at one of said stations for operating upon the lifts, a plurality of rolls carried by each of the lift-receiving devices, a pivotally mounted ring, and actuating means for lowering the ring into engagement with all of said rolls to depress all of said devices prior to each rotational step of the turret, said ring serving as a track upon

55 110 which the rolls traverse during the rotation of the turret, and for raising said ring when the turret has come to rest to permit all of the receiving devices to be yieldingly raised into operative position.

60 120 125 130 14. A heel-building machine having, in

combination, a movable lift-receiving device into which a heel is assembled, means for advancing said receiving device through successive stations, means for supplying a dry base-lift to said receiving device at one station, and means for delivering a plurality of pasted lifts upon said dry base-lift at another station.

15. A heel-building machine having, in combination, a movable lift-receiving device in which a heel is assembled, means for intermittently rotating said receiving device through successive stations, a magazine disposed adjacent one station for containing a stack of dry base-lifts, means at the same station for transferring a base-lift from said magazine to said lift-receiving device, and means at another station for pasting and delivering a plurality of pasted lifts upon the dry base-lift previously supplied to said receiving device.

16. A heel-building machine having, in combination, a rotatable turret comprising a plurality of lift-receiving devices adapted to be moved through a plurality of stations, means for supplying base-lifts to said receiving devices at one of said stations, means for assembling a plurality of pasted lifts upon said base-lifts at another station, and means for alining the lifts and nailing them together at another station.

17. A heel machine having, in combination, means including a breast gage for holding a loosely assembled heel, and reciprocable means operable in a direction towards the breast gage to effect an alinement of the breast and lateral edges thereof and operable in the opposite direction to withdraw the alined heel from said holding means.

18. A heel machine having, in combination, means including a breast gage for holding a loosely assembled heel, reciprocable means operable in a direction towards the breast gage to effect an alinement of the breast and lateral edges thereof and operable in the opposite direction to withdraw the alined heel from said holding means, and means operating between the alining and withdrawing movements of said reciprocable means for nailing together the component lifts of the heel.

19. A heel machine having, in combination, means including a breast gage for holding a loosely assembled heel, reciprocable means operable in a direction towards the breast gage to effect an alinement of the breast and lateral edges thereof and operable in the opposite direction to withdraw the alined heel from said holding means, means operating between the alining and withdrawing movements of said reciprocable means for subjecting the heel to pressure and nailing together the component lifts thereof, and means cooperating with said

reciprocable means during its withdrawing movement for effecting the release of the heel.

20. A heel-machine having, in combination, means comprising a breast gage for holding a loosely assembled heel, and a device movable from the rear of the heel toward said breast gage having members for engaging the lateral edges of the component lifts toward the rear of the heel at each side which, as the device is advanced, wipe along said side edges to the breast corners of the heel to effect a lateral alinement of said lifts.

21. A heel machine having, in combination, means comprising a breast gage for holding a loosely assembled heel, and an alining device movable as a unit in a rectilinear path towards said breast gage for alining the component lifts laterally by a wiping engagement with their side edges to the breast corners thereof and for subsequently engaging the rounded rear edges of the lifts to force them against the breast gage.

22. A heel machine having, in combination, means comprising a breast gage for holding a loosely assembled heel, and an alining device movable as a unit in a rectilinear path towards said breast gage and constructed and arranged to first laterally aline the component lifts by a wiping engagement throughout their side edges and then to aline the breast edges against the breast gage by pressure against their rounded rear edges.

23. A heel machine having, in combination, means embodying a breast gage for holding a loosely assembled heel, and means movable as a unit towards said breast gage for alining the breast and lateral edges of the heel comprising a pair of independent resiliently supported side alining members conforming to the ultimate side slope of the heel adapted to be yieldingly forced outwardly upon engagement with the heel, and means conforming to the ultimate curvature and pitch of the heel for engaging the rounded rear edges of the component lifts to force them against the breast gage.

24. A heel machine having, in combination, means embodying a breast gage for holding a loosely assembled heel, means movable as a unit towards said breast gage for alining the breast and lateral edges of the heel comprising a pair of independent resiliently supported side alining members conforming to the ultimate side slope of the heel adapted to be yieldingly forced outwardly upon engagement with the heel, and means conforming to the ultimate curvature and pitch of the heel for engaging the rounded rear edges of the component lifts to force them against the breast gage, and auxiliary means for forcing together said

side alining members to hold the lifts from displacement after the lateral alinement of the lifts has been effected.

25. A heel machine having, in combination, means embodying a breast gage for holding a loosely assembled heel, means movable as a unit towards said breast gage for alining the breast and lateral edges of the heel and comprising a pair of independent resiliently supported side alining members conforming to the ultimate side slope of the heel adapted to be yieldingly forced outwardly upon engagement with the heel, and means conforming to the ultimate curvature and pitch of the heel for engaging the rounded rear edges of the component lifts to force them against the breast gage, means for operating upon the alined component lifts of the heel, and means cooperating with said resiliently supported side alining members during the withdrawal of said alining means for spreading apart said members to release the heel.

26. A heel machine having, in combination, means for holding heel-piles of superposed lifts, automatic periodically operated means for nailing together the component lifts thereof, and means for automatically preventing the effective operation of said nailing means in the absence in said holding means of a heel-pile to be nailed.

27. A heel-building machine having, in combination, means for assembling a plurality of lifts in the form of a heel-pile, means for receiving said heel-pile, means for moving the heel-pile in said receiving device to a nailing station, means at said station for nailing together the component lifts of said heel-pile, and automatic means for preventing the effective operation of said nailing means in the absence in said receiving means of a heel-pile to be nailed.

28. A heel machine having, in combination, means for holding a heel-pile of superposed lifts, a nailing mechanism, means for moving said holding means to position the heel-pile therein for the nailing operation, and detecting means engaged by the heel as it is moved into nailing position for preventing the effective operation of said nailing mechanism whenever a heel is absent.

29. A heel machine having, in combination, nailing mechanism comprising a nail driver, a spring-actuated nail block to position a nail for the nail driver to operate upon, means for actuating said nail block to loading position, and means for restraining said nail block in said position, means for holding and positioning a heel to be nailed, and means for releasing said nail block restraining means only when a heel is positioned to be nailed.

30. A heel machine having, in combination, a periodically operating nail driving mechanism, a spring actuated nail block

normally restrained in its inoperative loading position, means for holding and presenting a heel in position to be nailed, and means engaged by the heel for releasing said nail block to cause it to feed a nail into position to be driven by said nail driving mechanism.

31. A heel-building machine having, in combination, means for periodically assembling a predetermined number of heel lifts in the form of a heel-pile, a plurality of lift-receiving devices adapted to be moved through successive stations, in one of which said devices successively receive the assembled heel-piles, and means for preventing the assembly of lifts if there is a failure to deliver all of the component lifts to said receiving devices.

32. A heel-building machine having, in combination, means for periodically assembling a predetermined number of heel lifts in the form of a heel-pile, a plurality of lift-receiving devices adapted to be moved through successive stations, in one of which said devices successively receive the assembled heel-piles, means disposed at the receiving station for measuring the height of the heel-pile delivered, and means dependent upon said measuring means for controlling the operation of said assembling means.

33. A heel-building machine having, in combination, means for periodically pasting a plurality of heel lifts and assembling them in the form of a heel-pile, a plurality of lift-receiving devices adapted to be moved through successive stations, in one of which said devices successively receive the assembled heel-piles, and means for measuring the height of each heel-pile delivered to said receiving devices and for automatically interrupting the operation of the machine if the heel-pile is too low.

34. A heel-building machine having, in combination, a lift-receiving device into which heels are assembled, means for advancing said receiving device through a plurality of stations, means for delivering a plurality of lifts into said receiving device, and means for measuring the height of the delivered heel and cutting off the power from the machine if the delivered heel is of improper height.

35. A heel machine having, in combination, nail driving means, a member against which the heel is positioned to receive a nail, a heel holder initially in a position below said member, means co-operating with said holder to raise it and cause a heel therein to engage said member, said means being constructed and arranged to raise an empty holder an amount sufficient to cause the holder to engage said member, and means for preventing an engagement of the holder with said member in the event no heel is in the holder.

36. A heel machine having, in combination, means for holding a heel, means for raising the holding means, a member against which the heel is raised, a nailing mechanism for driving a nail into said heel, means for detecting the presence of the heel in said holding means and for permitting the operation of the nailing means only when a heel is present, and means for limiting the upward movement of said holding means when a heel is absent therefrom.
37. A heel-building machine having, in combination a movable lift-receiving device, means at one station for assembling a plurality of lifts therein in the form of a heel-pile, means for moving said device and assembled heel-pile to an operating station, means normally tending to raise the lift-receiving device and adapted to permit it to be depressed as the lifts are progressively deposited, means for positively lowering the lift-receiving device prior to its movement from one station to another and permitting the device to be raised when its transferring movement has ceased, means at the operating station for engaging the upper surface of the heel when the device is raised, means disposed beneath said station for engaging said device and urging it upwardly to subject the heel to pressure, and means for driving a nail through the component lifts thereof.
38. A heel machine having, in combination, a heel support, means for initially yieldingly raising said heel support, a member against which the heel is raised, a normally retracted, spring-actuated member for engaging and lifting said heel support, means operating after the initial raising of said heel support to release said member and cause it to subject the heel to pressure between said support and said member, and means for driving a nail in the heel while so held.
39. A heel-building machine having, in combination, a movable lift-receiving device, means at one station for assembling a plurality of lifts therein in the form of a heel, means for moving said device and assembled lifts to an operating station, means normally tending to raise the lift-receiving device and adapted to permit it to be depressed as the lifts are progressively deposited, means for positively lowering the lift-receiving device prior to its movement from one station to another and permitting the device to be raised when its transferring movement has ceased, means at said operating station for engaging the upper surface of the heel when the device is raised, spring-actuated means disposed beneath said station for engaging said device and urging it upwardly to subject the heel to pressure, means for cooperating with said spring-actuated pressure applying means for rigidly positioning
- said means and positively supporting the lift-receiving device, and means for driving a nail through the component lifts of the heel when so supported.
40. A heel machine having, in combination, means for holding a heel, means for yieldingly raising the holding means, a member against which the heel is raised, means for alining the component lifts of the heel, means adapted to engage the holding means for subjecting the heel to pressure, means for rigidly supporting said holding means to provide a positive support therefor, and means for driving a nail into the heel while held in alinement and so positively supported.
41. A heel machine having, in combination, means for supporting a heel, a nail driving mechanism for driving a nail therein, and means for supplying a nail in position to be driven comprising a movable nail-supply block having a plurality of rows of perforations therein, each containing a nail, a nail tube for feeding nails from the nail-supply block into position to be driven, means for actuating the nail-supply block in steps to present the successive rows of perforations above the upper end of the nail tube, and means operating during periods of rest of said nail-supply block for stepping the upper end of the tube beneath each row of perforations and in registry therewith to permit the nails in said perforations to be successively fed through the tube into nail driving position.
42. A heel machine having, in combination, means for supporting a heel, a nail driving mechanism for driving a nail therein, and means for supplying a nail in position to be driven comprising a nail-supply block having a plurality of rows of perforations therein, each containing a nail, a nail tube for delivering the nails successively from the nail-supply block into position to be driven, and means for moving both the nail-supply block and the upper end of the nail tube in directions normal to each other to cause the nails in the nail-supply block to be successively fed through the tube into position to be driven.
43. A heel machine having, in combination, a heel holder including a breast gage against which the lifts of a heel-pile are stacked without regard to correct alinement, a lift alining device normally withdrawn from the heel-pile and movable to successively engage first the lateral breast edges of the component lifts and afterwards the rear edges thereof, and means for actuating said device to force the breast of the heel-pile into contact with said breast gage.
44. A heel machine having, in combination, a heel holder including a breast gage against which the lifts of a heel-pile are stacked without regard to correct alinement,

4. A lift alining device having members for engaging the lateral surface of the heel-pile at the breast corners and at the rounded back thereof, and means for actuating said device to effect first a transverse alinement of the lifts and thereafter a longitudinal alinement thereof against said breast gage.
45. A heel machine having, in combination, a heel holder including a breast gage against which the lifts of a heel-pile are stacked without regard to correct alinement, a lift alining device having members for engaging the lateral surface of the heel-pile at the breast corners and at the rounded back thereof, said members being constructed and arranged to act successively on the heel to engage the breast corners before its rounded back is engaged, and means cooperating with said device to hold the heel-pile from lateral displacement while the pile is pressed against said breast gage.
46. A heel building machine having, in combination, a rotatable turret comprising a plurality of lift receiving devices, means for intermittently rotating said devices through a plurality of stations, means for feeding a series of heel lifts one after another in a pile to each of said receiving devices when at one of said stations, and means at another station for operating on said heel-pile while retained in the device to which it was delivered.
47. A heel building machine having, in combination, a rigidly supported nailing mechanism, means for delivering a pile of heel lifts in position to be nailed, means for yieldingly compressing the heel-pile against said nailing mechanism when in nailing position, and means for rigidly supporting the heel-pile while the nail is driven.
48. A heel-building machine having, in combination, means for loosely assembling a plurality of lifts to form a heel, a lift alining device comprising a pair of wipers spaced apart to receive a heel between them, means for presenting the heel to said device, and means for relatively moving the heel and device to cause a traverse of the wipers along the entire lateral surface of the heel at each side thereof.
49. A heel-building machine having, in combination, means for loosely assembling a plurality of lifts to form a heel, a lift alining device comprising a pair of yieldingly mounted wipers spaced apart to receive a heel between them, means for presenting the heel to said device, and means for relatively moving the heel and device to cause a traverse of the wipers along the entire lateral surface of the heel at each side thereof.
50. A heel machine having, in combination, a heel holder, a nail driver, a nail holder, and means for supplying nails to the nail holder comprising a nail block apertured to receive a plurality of nails in rows,

a nail tube leading from the block to the holder, and means to advance the block to bring successive rows of nails in position for delivery through said tube after the exhaustion of the nails in each row.

51. A heel-building machine having, in combination, a pair of oppositely disposed lift alining wipers, means for loosely assembling a plurality of lifts and presenting the heel thus formed to the open end of said wipers, and means for relatively moving the heel and wipers to effect pressure on the opposite lateral surfaces of the heel and aline the lifts thereof.

52. A heel building machine having, in combination, means for periodically delivering successive series of heel lifts, a rotatable turret comprising a plurality of heel holders, means for assembling said successive series of lifts as they are delivered, and means for rotating said turret to bring said heel holders into position to receive successively the lifts of each series one by one as they are assembled.

53. A heel building machine having, in combination, means for delivering successive series of heel lifts in a row, a rotatable turret at the end of the row comprising a plurality of heel holders for receiving said series of lifts, means for feeding the delivered lifts onto a holder in a pile, and means for rotating the turret intermittently to bring each heel holder into position to successively receive a pile of lifts.

54. A heel-building machine having, in combination, means for delivering a plurality of lifts in a row, means for feeding said lifts to an assembling device at the end of the row, said assembling device, means for transferring the assembled heel lifts to an alining station, and means acting successively to aline the lifts and secure them together at said station.

55. A heel-building machine having, in combination, means for delivering a plurality of lifts in a row, means for feeding said lifts to an assembling device at the end of the row, said assembling device, means for transferring the assembled heel lifts to an alining station, spaced alining wipers at said station, means for causing said wipers to press the lifts from opposite sides into lateral alined relation, and means for nailing the alined heel.

56. A heel-building machine having, in combination, means for collecting a row of lifts in the form of a heel, resilient wipers at the end of the row for engaging and alining the lifts laterally, means for pasting the lifts as they are collected, and means for nailing the pasted and alined heel.

57. A heel machine having, in combination, a rotatable turret, a plurality of heel holders arranged about the periphery of the turret, and lift assembling means con-

structed and arranged to deliver to each holder a succession of lifts sufficient for a heel blank, said lift assembling means operating radially of the turret.

5 58. A heel machine having, in combination, a horizontally rotatable turret, a plurality of heel holders arranged about the periphery of the turret, and means operating radially of the turret to assemble lifts into the holders.

59. A heel machine having, in combination, a rotatable turret carrying a plurality of holders in which lifts may be assembled to form heels, a source of supply of previously formed lifts, and means for removing lifts from the source of supply and assembling them into the holders by movement in their own planes.

60. A heel machine, having in combination, a turret having a plurality of peripheral heel holders each provided with a heel-receiving seat in a horizontal plane, a series of magazines adapted to hold vertical stacks of previously formed lifts, means for transferring lifts from said magazines and onto said seats without turning the lifts

from their horizontal position, and means for rotating the turret to permit said seats to receive lifts successively.

61. A heel machine, having in combination, a turret having a plurality of peripheral heel holders each provided with a heel-receiving seat in a horizontal plane, a source of supply of previously formed lifts, means for rotating the turret relatively to said source of supply, and means for feeding lifts in their own planes to said seats as the turret rotates, sufficient in number to form a heel blank on each seat.

62. A heel machine, having in combination, an intermittently rotatable turret having a plurality of peripheral heel holders each provided with a heel-receiving seat in a horizontal plane, means adjacent the orbit of the turret for holding a plurality of lifts all arranged horizontally, and means for supporting and operating on said lifts to advance them edgewise and deliver to each seat a number of lifts sufficient for a heel blank.
